DISPLAY HOLDER FOR TWIST DRILL PACKAGES

Stanley G. Smith, P.O. Box 447, Saugatuck, Mich.

Filed Apr. 4, 1963, Ser. No. 74,296

Term of patent 14 years

(Cl. D80—10)

FIG. 1 is a perspective view of the display holder for twist drill packages showing my new design; and

FIG. 2 is an end elevational view thereof.

The characteristic features of my design reside in the specific configuration of the package supporting arms in association with a conventional wall board supporting member as shown.

I claim:

The ornamental design for a display holder for twist drill packages, as shown and described.
